FEED MECHANISM

Joseph R. Guess, Rosemead, Calif.

Application July 1, 1950, Serial No. 171,642

5 Claims. (Cl. 140—129)

1

This invention relates to a mechanism for feeding a punch press or like machine, the same contemplating intermittent continuous feed of wire, rod, etc.

In the production of metal screens of large mesh, the cross wires or rods may be initially produced on a punch press that forms a series of offset crimps in each wire or rod. These are later interwoven with longitudinal wires or rods to form a screen. The gauge or mesh size of the screen varies as desired. Thus, the spacing of the crimps formed in the cross wires is subject to change according to the gauge.

For reasons of economy of manufacture, it is contemplated that wires or rods having crimps spaced exactly as desired be produced by one punch press equipped with a suitable die. It is an object of this invention, therefore, to provide a novel and improved wire feed mechanism for such a press that will produce wires or rods crimped on various spacings.

Since the gauge or mesh size of the screens may vary greatly or only in small increments, it is another object of the invention to provide a feed mechanism that may be quickly adjusted to vary the feed of a wire or rod in small increments throughout a wide range so that the spacing of the crimps formed by a press feed by said mechanism is exactly as desired.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a front elevational view of a feed mechanism according to the present invention, the same being shown in operative association with a conventional punch press.

Fig. 2 is an enlarged partial elevational and partial sectional view as taken on line 2—2 of Fig. 1.

Fig. 3 is a similarly enlarged plan sectional view as taken on line 3—3 of Fig. 1.

Fig. 4 is a view of a fragmentary portion of a wire or rod produced by the punch press.

2

The fragmentary portion of a punch press shown in Fig. 1 has a bed 5 provided with a conventional bolster 6 that mounts a die 7 for forming crimps 8 in a wire or rod 9. The usual ram cooperating with die 7 is not shown. However, the same is of conventional design and is reciprocatively driven by a shaft 10 controlled by a one-revolution clutch and having the usual fly wheel. It is understood that for each revolution of shaft 10, a crimp 8 is formed in wire or rod 9. According to the invention, feed mechanism 11, preferably attached to and carried by the press, is provided for intermittently feeding wire or rod 9 so that crimps 8 are spaced as desired.

The feed mechanism 11 comprises, generally, a support bracket 12 provided with a sloping transverse slideway 13, a slide 14 in said slideway, a frame 15 carried by the slide, a stepped feed roll or wheel 16 carried by the frame, an auxiliary frame 17 mounted in frame 15 and carrying an idler feed wheel 18 operatively associated with wheel 16, adjusting means 19 for frame 17, locking means 20 for slide 14 and for the means 19, adjusting means 21 for slide 14, a set of interchangeable ratchet wheels of which one wheel 22 is connected to feed wheel 16, a drive arm 23 for ratchet wheel 22, and means 24, driven from shaft 10 of the press, for oscillating arm 23.

Bracket 12 is preferably formed as a casting having a transversely sloped base wall 25 arranged to extend laterally of the press bed 5, the bracket being secured to an edge of said bed as by suitable bolts 26. The bracket shown is provided with a lateral extension 27 which, in a conventional manner, mounts wire or rod straightening wheels 28 that serve to straighten wire or rod 9 as the same is removed from a roll thereof, and fed to die 7.

The slideway 13 comprises a pair of ways 29 formed on or affixed to the upper surface of wall 25 and sloped according to said wall. Between said ways 29, wall 25 is formed with an elongated slot 30.

Slide 14 comprises a block that has its lower sloping surface 31 resting on sloping wall 25 and its upper surface 32 is horizontal. Said slide is, therefore, generally wedge-shaped. Lateral flanges 33 on the slide are engaged in ways 29.

Frame 15 comprises a pair of spaced standards 34 affixed to slide 14 and extending upwardly from face 32 thereof, said standards, at their upper ends, serving to revolubly mount a transverse shaft 35. Inreaching hubs 36 are provided for the shaft 35 and serve also to locate feed wheel

16 substantially centrally between standards 34.

Feed wheel 16 is here shown with five steps or lands 37, although the number may vary, as desired. The steps each comprise an individual feed wheel, as will later be seen, and the cylindrical faces thereof are preferably knurled for non-slipping feed engagement with wire 9. It will be evident that the step having the smallest diameter will feed wire 9 a commensurately shorter distance than will the step having the largest diameter, the intermediate steps feeding proportionally. It will be seen that the steps 37 define a certain transverse angle relative to the plane of rotation of the wheel. It is at this angle that wall 25 and guideway 13 are disposed.

Auxiliary frame 17 is formed as a U-shaped member having a base 38, spanning between standards 34, and legs 39 residing against and having sliding engagement with the inner faces of said standards. Guides 40 on the standards confine frame 17 and hold the same in vertical alignment with the standards.

Idler feed wheel 18 is carried by frame 17 between its legs 39 and is held in vertical alignment with feed wheel 16 between hubs 41 extending inwardly from said legs. Wheel 18 is provided with steps or lands 42 similar to those of wheel 16, but the same are oppositely arranged with the largest step of one wheel vertically aligned with the smallest step of the other. Wheel 18 may be considerably smaller than wheel 16, as shown, and while the same may be knurled, knurling is not essential, since non-slippage feed of the wire is achieved by wheel 16.

Adjusting means 43 comprises a threaded stem 43 that engages in a threaded bore in slide 14 and extends through slot 39 from beneath bracket wall 25. The upper end of said stem impinges on base 38 of frame 17. It is evident that frame 17 and idler wheel 18 thereon may be adjusted relative to the slide to bring wheel 18 to adjusted position relative to wheel 16 to effect feed of a wire 9 when the latter wheel is rotated. The adjustment is made according to the diameter of said wire. A suitable handle 44 is provided on the lower end of stem 43 to facilitate rotational adjustment of said stem.

Locking means 20 comprises an internally threaded sleeve 45 having a handle 46 and threadedly engaged with stem 43. A wedge-shaped block 47 is interposed between the upper end of said sleeve and the under face of wall 25 and takes the thrust of said sleeve along the axis of stem 43. It will be clear that sleeve 45, through stem 43, draws slide 14 tightly against bracket wall 25 to lock said slide and the parts carried thereby.

Adjusting means 21 comprises a threaded stem 48 that passes through the threaded bore of a bracket 49 affixed to the rear of bracket 12, a handle 50 for rotating said stem, a lock nut 51 for locking the stem against rotation and engaged against bracket 49, and a grooved and headed end 52 on said stem engaged in a seat 53 formed in slide 14. Stem 48 is mounted at the angle of wall 25 so that adjusting movement thereof is in the plane of said angle.

Since die 1 has a fixed position that dictates the line of feed of wire 9, it will be seen that the means 21 is employed to bodily adjust the feed wheels 16 and 18 to align those steps 37 and 42 of said wheels that are desired to engage the wire. The adjustment shown is for a feed of intermediate length, while rearward adjustment (to the left in Fig. 2) will provide for a shorter

feed, and forward adjustment, a longer feed. The feed variations are a function of the relative diameters of the lands 37 and the length of feed increases or decreases accordingly.

5 Each ratchet wheel 22 comprises a disc 54 having a set of peripheral ratchet teeth 55, the same being uniformly spaced. An eight-toothed wheel is shown and it will be apparent that the number of teeth may vary so that the drive arm 23 10 may intermittently drive that wheel which is mounted on shaft 35 through angular increments according to the angles included between the ratchet teeth. An eight-toothed wheel will be driven through angular increments of 45° to impart 15 a linear travel of wire 9 of a certain length; a six-toothed wheel, for instance, will be driven through an angular increment of 60° to impart a linear travel of the wire of a commensurately greater length; and a ten-toothed wheel will, 20 therefore, impart a linear travel to wire 9 that is commensurately shorter. Thus, by selection of a ratchet wheel 22 having a suitable number of teeth, and by adjusting drive wheel 16 to bring the desired step 37 thereof into feeding engagement with the wire, a wide range of feed increments may be achieved, each varying but slightly relative to the other. The feed variations may be further minimized by providing some of the ratchet wheels with an odd number of teeth and 25 providing for arm 23 to engage alternate teeth, rather than each one successively. For example, the exact desired length of feed may be shorter than can be achieved by the 45° drive of an eight-toothed wheel and longer than can be achieved by the 40° drive of a nine-toothed wheel. By using a seventeen-toothed wheel, a 42 $\frac{1}{17}$ ° drive may be obtained when every other tooth thereof is engaged by arm 23.

The selected ratchet wheel 22 is mounted on 30 shaft 35 and is clamped thereon by a plate 56 locked up by a nut 57. To insure that said wheel does not slip relative to wheel 16, a drive pin 58, 35 on a backing hub 59 for wheel 22, is employed.

Drive arm 23 is mounted on shaft 35 to freely 40 oscillate thereon, said drive arm having a housing 60 on the end thereof for a spring-urged drive dog 61 that rides the periphery of wheel 22 and engages notches or teeth 55 thereof. A rearward lateral extension 62 is provided near or at the 45 end of said arm.

Drive arm 23 is mounted on shaft 35 to freely 50 oscillate thereon, said drive arm having a housing 60 on the end thereof for a spring-urged drive dog 61 that rides the periphery of wheel 22 and engages notches or teeth 55 thereof. A rearward lateral extension 62 is provided near or at the 55 end of said arm.

Drive arm 23 is mounted on shaft 35 to freely 60 oscillate thereon, said drive arm having a housing 60 on the end thereof for a spring-urged drive dog 61 that rides the periphery of wheel 22 and engages notches or teeth 55 thereof. A rearward lateral extension 62 is provided near or at the 65 end of said arm.

Drive arm 23 is mounted on shaft 35 to freely 70 oscillate thereon, said drive arm having a housing 60 on the end thereof for a spring-urged drive dog 61 that rides the periphery of wheel 22 and engages notches or teeth 55 thereof. A rearward lateral extension 62 is provided near or at the 75 end of said arm.

Drive arm 23 is mounted on shaft 35 to freely 80 oscillate thereon, said drive arm having a housing 60 on the end thereof for a spring-urged drive dog 61 that rides the periphery of wheel 22 and engages notches or teeth 55 thereof. A rearward lateral extension 62 is provided near or at the 85 end of said arm.

Drive arm 23 is mounted on shaft 35 to freely 90 oscillate thereon, said drive arm having a housing 60 on the end thereof for a spring-urged drive dog 61 that rides the periphery of wheel 22 and engages notches or teeth 55 thereof. A rearward lateral extension 62 is provided near or at the 95 end of said arm.

Since the axes of shafts 10 and 35 are transverse to each other and are also vertically offset, and since extension 63 rotates in a plane transverse to the plane of oscillation of arm 23, the swivel 66, pivot 69 and ball-and-socket 70 cooperate to translate the rotary motion of shaft 10 into oscillating movement of arm 23 and, therefore, intermittent feed movement of feed wheel 16. The stroke of the pitman may be adjusted by selection of pivot holes 71 therein for pivot 69 and a corresponding adjustment of head 67 relative to the axis of shaft 10. Thus, the swing of arm 23 may be varied according to the 100 number of teeth in wheel 22.

Ratchet dog 61, on the recovery stroke of arm 23, may over-run the tooth 55 next to be engaged thereby and pick up said tooth during the feed stroke. In order to insure against back-lash and to hold drive wheel 16 during the recovery stroke of arm 23, brake means is provided. The same is shown as a drum 72 on shaft 35 and a brake shoe 73 engaged with said drum and connected to frame 15 at 74.

While the invention that has been illustrated and described is now regarded as the preferred embodiment, the construction is, of course, subject to modifications without departing from the spirit and scope of the invention. It is therefore not desired to restrict the invention to the particular form of construction illustrated and described, but to cover all modifications that may fall within the scope of the appended claims.

Having thus described the invention, what is claimed and desired to be secured by Letters Patent is:

1. In a wire feed mechanism, in combination, a sloping support having its angle of slope transverse to the line of feed of a wire, a bracket slidably adjustable on said support along the angle of slope thereof, a pair of feed wheels carried on parallel axes by said bracket and between which extends said line of wire feed, a drive for one of said wheels, each wheel being provided with a plurality of annular lands of successively different diameter and the angle defined by the lands of each wheel where the same engage the wire being the same as and parallel to the angle of slope of the support, and means to adjust the spacing between the lands of the respective wheels.

2. In a wire feed mechanism, in combination, a sloping support having its angle of slope transverse to the line of feed of a wire, a bracket slidably adjustable on said support along the angle of slope thereof, a pair of feed wheels carried on parallel axes by said bracket and between which extends said line of wire feed, each wheel being provided with a plurality of annular lands of successively different diameter and the angle defined by the lands of each wheel where the same engage the wire being the same as and parallel to the angle of slope of the support, means to adjust the spacing between the lands of the respec-

tive wheels, comprising an auxiliary bracket slidably carried by the mentioned bracket and mounting one of said wheels and an adjusting stem engaged with the auxiliary bracket and carried by the sloping support, and means to intermittently drive the other of said wheels.

3. In a wire feed mechanism according to claim 1: the diameter of the smallest annular land of the driven wheel being larger than the diameter of the largest annular land of the other wheel.

4. In a wire feed mechanism according to claim 1: the drive comprising an oscillating arm on the axis of the driven wheel, a ratchet wheel fixedly mounted on said axis and provided with a set of uniformly spaced ratchet teeth, and a dog on said arm successively engaging said teeth during oscillation of the arm to intermittently drive the latter feed wheel and, thereby, intermittently feed the wire.

5. In a wire feed mechanism according to claim 1: the drive comprising an oscillating arm on the axis of the driven wheel, a ratchet wheel fixedly mounted on said axis and provided with a set of uniformly spaced ratchet teeth, and a dog on said arm successively engaging said teeth during oscillation of the arm to intermittently drive the latter feed wheel and, thereby, intermittently feed the wire, said ratchet wheel comprising one of a set of such wheels in which each wheel has a different number of uniformly spaced ratchet teeth.

JOSEPH R. GUESS.
